UNITED STATES PATENT OFFICE.

ALFRED CROSSLEY, OF WASHINGTON, DISTRICT OF COLUMBIA, ASSIGNOR TO THE HARTMAN ELECTRICAL MANUFACTURING COMPANY, OF MANSFIELD, OHIO, A CORPORATION.

VARIOCOUPLER.

Application filed August 16, 1922. Serial No. 582,254.

To all whom it may concern:

Be it known that I, ALFRED CROSSLEY, a citizen of the United States, residing at Washington, in the District of Columbia, have invented a certain new and useful Improvement 5 in a Variocoupler, of which the following is a specification.

My invention relates broadly to signaling systems and more particularly to a variocoupler for connection in radio frequency circuits in such systems.

One of the objects of my invention is to provide a variocoupler having large electromagnetic coupling with minimum electrostatic coupling.

Another object of my invention is to provide a variocoupler construction by which a more perfect zero coupling may be obtained than in any construction of variocoupler heretofore proposed.

Another object of the invention is to provide a variocoupler which may be connected in a circuit and arranged to secure extremely selective tuning of the circuits.

Other objects of the invention will appear from the specification hereinafter following by reference to the accompanying drawings in which:

Figure 1 is a side elevation of the variocoupler partially in half section; Fig. 2 is a front elevation of the variocoupler partially broken away to show the rotor in section on lines 2—2 of Fig. 1; Fig. 3 is a top plan view of the variocoupler; Fig. 4 is a perspective view of the variocoupler; Fig. 5 is a perspective view of one form of shaft employed as a mounting for one side of the rotor of the variocoupler; Fig. 6 is a partial sectional view through line 6—6 of the rotor shaft of the variocoupler shown in Fig. 1; Fig. 7 is a view of one form of bearing support and terminal for one end of the rotor of the variocoupler; Fig. 8 is a wiring diagram showing the variocoupler used in different positions in a regenerative electron tube radio receiving circuit; and, Fig. 9 is a wiring diagram showing the variocoupler used in a radio receiving circuit employing electron tubes arranged in a radio frequency amplifying circuit for the reception of radio signals.

In my construction of variocoupler I obtain a very large electromagnetic coupling of the circuits connected with the windings thereof by reducing to a minimum the effects

of the electrostatic coupling between the circuits, whereby, to all practical purposes, the electrostatic field opposing the electromagnetic field is eliminated, permitting the maximum building up of the electromagnetic field. The electrostatic coupling of my variocoupler is rendered so small that it is negligible, with the result that zero coupling and a maximum true magnetic coupling with varying degrees of coupling therebetween may be secured. The present variocoupler is particularly useful as a tuning device in association with radio frequency electron tube amplification. In radio frequency amplification the securing of zero coupling or very nearly zero coupling is of great importance. In present forms of variocouplers the passage of electrostatic energy from one circuit to another has the tendency of annulling the tuning effects and greatly reducing the selectivity of adjustment of the circuits. However, with the negligible electrostatic capacity of my variocoupler, and when working near the zero coupling position, both circuits may be tuned with great accuracy. This selectivity in tuning is particularly desirable for the reception of signals on different bands of wavelengths within close proximity to each other.

In obtaining these results I provide a variocoupler including a rotor and a stator forming the primary and secondary windings which connect to the coupled circuits. The stator of my variocoupler is tubular or cylindrical in form and its winding is arranged with minimum dielectric loss. The rotor of my variocoupler is formed in the shape of a disk mechanically mounted in a plane passing through the diameter of the stator and at right angles to the axis thereof. The rotor comprises a hub with spokes radially positioned therein. The winding carried by the rotor is formed in the manner of a spider web or flat winding having its turns interwoven upon the spokes and spirally built up to occupy the length of the spokes. The dielectric losses in both the primary and secondary windings are reduced to a minimum by reducing the area of contact of the turns of each coil with the dielectric. The variocoupler may be connected in a variety of radio frequency circuits either in radio signaling systems or in carrier wave line wire systems. When em-

ployed in the tuning circuit before a radio frequency electron tube amplifier the stator or primary winding is connected in the antenna ground system while the rotor is connected to the input circuit of the first stage of radio frequency electron tube amplification. Maximum electromagnetic coupling occurs when the flat area of the rotor is in a position parallel with the direction of the turns of the winding upon the stator while zero coupling occurs when the flat area of the rotor is approximately at right angles with the direction of the turns of the winding upon the stator. Intermediate degrees of coupling are obtained within the zero and maximum positions. In regenerative electron tube circuit arrangements the stator of the variocoupler may be connected in the grid circuit in series with the rotor of the variocoupler forming the tuning circuit coupling. The rotor of the first mentioned variocoupler is connected as a tickler coil in the plate circuit and regeneration adjusted by changing the coupling between the rotor and stator.

Referring to the drawings, reference character 1 represents a base support with variocoupler. The stator winding 2 of the variocoupler is wound upon an insulated cylindrical support 4. The support 4 is secured to the base 1 by members 5, one of which provides means for anchoring the end of the stator winding 2 secured to binding post 6. The support 4 has a minimum of its area exposed to contact with the turns of the stator winding. In accomplishing this object I provide grooves 7 in the insulating material. The grooves greatly reduce the dielectric losses at the same time that mechanical strength is retained in the support in that the grooves are not cut entirely through the support. Within the cylindrical stator support 4 I pivot a flat spider web wound rotor having its winding indicated at 8. The rotor is formed upon a hub 10 with an uneven number of round spokes 12 projecting therefrom. Through one of the spokes 14 a rod 15 is passed being secured within the hub by nut 16 upon the threaded end of rod 15. The outer end of rod 15 carries flange 17 and bearing portion 18. The bearing does not contact with the walls of the cylindrical support 4 through which it passes, but is entirely supported in bearing strip 20 with leaf spring member 21 interposed between the inner surface of strip 20 and the flange 17. The strip 20 is screwed to the stator support 4.

At the opposite side of the rotor I provide a bearing shaft 22 formed by reason of the uneven number of spokes with a strip 24 embracing by means of screws 25 and 26 two of the spokes radiating from the hub. The bearing shaft 22 is provided with flange 27 adjacent the member 24 providing a face

against which the leaf spring 28 exerts a constant pressure. The leaf spring 28 is secured in position by member 29 screwed to the outer walls of the stator support 4. The constant resilient force of leaf springs 21 and 28 provide means for rigidly adjusting the rotor in any position with reference to the stator winding. The inner end of the rotor winding 8 is secured to rod 15 and an electrical connection provided through the spoke 14, bearing 18, and resilient spring 21 to binding post 30. The winding upon the rotor frame is spirally formed and fashioned in a manner resembling a spider web woven about the spokes radiating from the hub. The outer end of the rotor winding is connected to the member 24 and the electrical connection taken through shaft 22, leaf spring 28 and member 29 to binding post 31.

The variocoupler may be mounted immediately behind a panel, and for permitting this assembly I provide screws 32 and 34, the screw 32 passing into member 29 and the screw 34 passing through bushing 35 and into the stator support 4. The shaft 22 projects through the panel mounting and is provided with any desired form of insulated knob by which adjustment of the position of the rotor with reference to the stator may be obtained as, for example, in dotted line positions 41 and 42. The stator winding anchored at binding post 6 may be provided with intermediate connection points 36, 37, 38 and 39, and the end of the winding anchored to binding post 40. Flexible connections may be taken from these several points to contact points upon the panel and a switch provided to select the desired number of electrical turns in the stator circuit.

While I have shown the rotor as comprising a hub and a plurality of spokes screwed into the periphery of the hub, it will be understood that the rotor frame may be moulded or formed from insulating material in one integral mass.

The variocoupler may be used in a variety of electrical circuits where extreme accuracy in tuning is desired with a minimum electrostatic coupling and a large electromagnetic coupling. In Fig. 8 I show the application of the present device in two different positions of an electron tube regenerative radio receiving circuit. The variocoupler 44 has its stator winding 2 connected in an antenna ground system and its rotor 8 connected to the input circuit of the electron tube regenerative receiver. The variocoupler 45 has its stator 2 connected in the grid circuit of the electron tube 46 and its rotor connected in the plate circuit of the electron tube 46 whereby the desired feeding back of energy from the plate circuit to the grid circuit may be secured by adjustment of the relative position of rotor 8 with

respect to the stator 2, while selectivity in tuning may be secured by adjustment of the relative positions of the stator and rotor of the variocoupler 44 while response of the signal energy is secured in telephone receivers 47.

In Fig. 9 I show the application of the variocoupler to a radio frequency amplifier used at a radio receiver. The variocoupler 48 has its stator winding 2 connected in an antenna ground system and its rotor 8 connected to the input circuit of electron tube 49 forming the first stage of the radio frequency amplifier. Electron tubes 50 and 51 are connected to form succeeding stages of radio frequency amplification while electron tube 52 is arranged as a rectifier and the energy amplified at audio frequency through the required number of stages represented diagrammatically by the single stage employing electron tube 54. The responsive device 55 is connected in the final stage of audio frequency amplification. As heretofore pointed out, the present form of variocoupler is particularly useful in radio frequency amplification by reducing to a negligible degree the passage of electrostatic energy from the antenna circuit to the input circuit of the radio frequency amplifier but providing a maximum electromagnetic coupling, obtaining thereby real tuning.

My arrangement provides means for introducing sufficient electromagnetic coupling to neutralize the effects of capacity coupling by swinging the rotor to a position in which the electromagnetic coupling counteracts any remaining effects of electrostatic coupling, at which point zero magnetic coupling will be obtained. Further movement of the rotor in the proper direction gives magnetic coupling with great selectivity, enabling segregation of signals on slightly separated frequencies.

While I have described my invention in certain embodiments I intend no limitations other than are imposed by the scope of the appended claims.

What I claim is:

1. A variocoupler comprising a cylindrical support, a primary winding on said support, a flat spider web wound secondary mounted adjacent one end of said support, and means for rotating said spider web wound coil relatively to said primary coil.

2. A variocoupler comprising a cylindrical support, a winding carried by said support, a frame pivotally mounted within said support, a winding carried by said frame, the conductors of said winding being arranged at all times approximately in a plane passing through a diametrical line through said cylindrical support, and means for rotating said windings relative to each other.

3. A variocoupler comprising a tubular

support, a winding carried by said support, a flat disk rotor comprising an insulated hub, arms radially positioned in said hub, a winding carried by said arms, and means for rotating said disk relative to said tubular support.

4. A variocoupler comprising a cylindrical member, a winding carried thereby, a flat disk rotor comprising an insulated hub, an uneven number of arms radially positioned in said hub, a winding interwoven about said arms, and means through one of said arms and attached to another two of said arms for pivotally mounting said disk relative to said cylindrical stator.

5. A variocoupler comprising a cylindrical member, a flat disk rotor comprising an insulated hub, arms radiating from said hub, a winding carried by said arms, means for pivotally mounting said disk within said cylindrical member comprising separate shafts, flange faces on said shafts, metallic fittings mounted on said cylindrical member, and resilient means between said fittings and said flange faces whereby said rotor may be adjusted in position relative to said cylindrical member.

6. A variocoupler comprising a cylindrical support, a winding carried by said support, a frame within said support, a pair of shafts for pivotally mounting said frame relative to said support, a winding carried by said frame, the ends of said winding being connected to said shafts, the conductors in said windings being arranged at all times approximately in a plane passing through a diametrical line through said cylindrical support, and means for rotating said windings relative to each other.

7. A variocoupler comprising in combination a cylindrical member, a plurality of supporting faces separated by spaces over the area of the surface thereof, a stator winding carried by said cylindrical member, the turns of said winding contacting with said supporting faces and passing over said spaces, a flat rotor pivotally mounted within said cylindrical member comprising a hub having arms radiating therefrom, a rotor winding having its turns tangentially contacting with said arms whereby dielectric loss in said stator and rotor are minimized.

8. A variocoupler comprising a pair of windings, one of which is rotatable and the other stationary, the rotatable winding having extremely small electrical capacity with the stationary winding, and being movable into a plane approximately in the line of the axis of the stationary windings for introducing sufficient electromagnetic coupling to neutralize the effects of capacity coupling whereby said variocoupler obtains substantially zero electromagnetic coupling.

9. A variocoupler, comprising in combi-

nation a cylindrical stator, a flat rotor pivotally mounted relative to said stator, a winding on said cylindrical stator, a separate winding on said flat rotor, said last named winding being arranged in such manner that only the width of a single turn lies directly adjacent said first named winding.

10. A variocoupler, comprising in combination a cylindrical stator, a flat rotor pivotally mounted relative to said stator, a winding on said cylindrical stator, a sepa-

rate winding on said flat rotor, said last named winding comprising a conductor terminating adjacent the center of said rotor and being spirally wound to an opposite terminal adjacent the periphery of said rotor, said winding being arranged in such manner that only the width of one conductor lies directly adjacent said first named winding whereby electrostatic transfer of energy between said windings is substantially nil.

ALFRED CROSSLEY.
